UNITED STATES PATENT OFFICE.

FREDERICK DANIEL KEEES, OF BEATRICE, NEBRASKA.

CORN-HUSKER.

SPECIFICATION forming part of Letters Patent No. 763,984, dated July 5, 1904.

Application filed August 11, 1898. Serial No. 688,397. (No model.)

To all whom it may concern:

Be it known that I, FREDERICK DANIEL KEEES, residing at Beatrice, in the county of Gage and State of Nebraska, have invented 5 certain useful Improvements in Corn-Huskers; and I do hereby declare that the following is a full, clear, and exact description of the invention, such as will enable others skilled in the art to which it appertains to make and use 10 the same, reference being had to the accompanying drawings, which form a part of this specification.

This invention relates to an improvement in corn-huskers.

15 The object of my invention is to provide a corn-husker which shall be adjustable, so that it will fit any sized hand and thumb, as will be more fully described hereinafter.

In the accompanying drawings I have shown, 20 in Figure 1, a perspective view of a corn-husker embodying my invention. Fig. 2 shows a top view of the leather blank comprising the main portion of my invention, Fig. 3 showing the outline of a husker embodying my invention, while Fig. 4 shows a view disclosing the outline of the shield as is used in my invention.

In the accompanying drawings, A represents 25 a preferable leather blank which has an outward-extending portion 1, an outward-extending portion 3 at the point opposite the first extension, and an intermediate outwardly-extending thumb portion 2, as is clearly shown in Fig. 2. While this blank may be of leather, 30 any other suitable material, such as cloth, may be used. At a suitable point this blank A is provided with a strap 8, the buckle of which is secured near the end marked 3, while the remaining end of the strap is secured at and 35 near the end 1 of the blank, which forms a holder. To this holder A is secured a husking-knife plate B, near the end marked 2, which end 2 is adapted to come adjacent to the thumb of the operator's hand, while the 40 portions 1 and 3 of the holder are intended to fit around the operator's wrist. The husking-knife plate B is provided with an outward extension 4, which extension is slightly curved, so as to fit around the bottom of the opera- 45 tor's thumb, while the remaining portion of

the plate, which is approximately in the shape of a triangle, is provided with an outwardly-extending and recurved husking-knife blade 5, and below this knife is an oval portion 6, which is provided with openings adapted to 55 receive the rivets α , by means of which this husking-knife is secured to the holder. This knife-plate B may be made of any suitable size or material, and extending from the same is the shield or holder C, which is also secured 60 to the holder A by means of the rivets α . As shown, this shield or holder C is slightly dished, so as to accommodate the lower portion of the palm of the hand.

Secured to the holder A near the thumb portion 2 is a second strap 10, which extends from the lower oval portion 6 of the knife outward and recures, passing through the opening 7 within the extension 4, so that the thumb-loop 9 is formed, by means of which 65 the holder A is adjustably secured to the thumb of the operator, the strap 10 being adapted to recurve and pass over the back of the hand and be secured within the buckle 12, secured to and forming part of the strap 11, 70 which strap is secured near the end 3 of the holder A, as is shown in Fig. 1. The holder A is further secured to the wrist of the operator by means of the strap 8, which curves over the knife B backward, passing over the 75 back of the hand, being finally secured within the buckle 12, forming part of this strap 8. From this it will be seen that the holder A is secured to the operator's hand, practically covering the palm of the same, while 80 the back of the hand is left free, except that the two straps 8 and 10 pass over in securing the holder. By virtue of the strap 10 passing through the opening 7 of the holder this 85 loop 9 can be given any suitable size, so as to 90 accommodate either the thumb of a boy or man, and so, also, can the holder A be adjusted to any sized hand.

Having thus described my said invention, what I claim as new, and desire to secure by 95 United States Letters Patent, is—

A corn-husker comprising the combination with an approximately elongated flexible holder, of a strap skirting, said holder along one of its longest edges and projecting be- 100

yond the same, of the buckle secured to one end of the strap, of a dished shield approximately triangular in outline secured to said holder, the apex end of said shield extending 5 toward the buckle end of aforesaid strap, a stub-buckle-provided strap secured near the apex end of said shield, a rivet passing through said shield and said stub-strap near the apex end to secure said shield and stub-strap to 10 said holder, a knife-plate provided with a recurved knife, said knife-plate being provided with a perforation near one end, said plate being secured at its opposite end to the base edge of said approximately triangular-shaped

shield, of rivets passing through said knife- 15 plate and said shield to secure the same to said holder, and a third strap secured to said holder and adapted to pass through the perforation within said knife-plate and engage the buckle of said stub-strap, all arranged sub- 20 stantially as shown.

In witness whereof I have hereunto placed my signature in the presence of two witnesses.

FREDERICK DANIEL KEEES.
